UNITED STATES PATENT OFFICE

92,779

DESIGN FOR A VISUAL ACUITY TESTING PROJECTOR

Hugo E. Tensen, Dayton, Ohio, assignor of one-half to Arthur P. Wheelock, Des Moines, Iowa

Application January 31, 1934, Serial No. 50,564

Term of patent 7 years

To all whom it may concern:

Be it known that I, HUGO E. TENSEN, a citizen of the United States, and a resident of Dayton, in the county of Montgomery and State of Ohio, have invented a certain new, original, and ornamental Design for a Visual Acuity Testing Projector, of which the following is a specification, reference being had to the accompanying drawing, forming part thereof:—

Figure 1 is a perspective view taken from the front of the projector and showing in dotted lines

a base and a lens tube which can be used in connection with the projector; and

Figure 2 is a detail perspective view taken from the rear of the projector, showing the projector per se.

I claim:

The ornamental design for a visual acuity testing projector, substantially as shown and described.

HUGO E. TENSEN.
